PORTRABLE FOLDABLE PARTITION

Harry Cohn, Jr., Portola Valley, Arthur W. Le Gette, Orinda, and William G. Papsco, Portola Valley, Calif., assignors to Papsco Building Products Inc., a corporation of California

Filed Aug. 26, 1968, Ser. No. 13,285

Term of patent 14 years

Int. Cl. D6—99

U.S. Cl. D33—1

FIG - 1

FIG. 3

FIG. 1 is a perspective view of a portable foldable partition showing our new design;

FIG. 2 is another perspective view taken from one side thereof; and

FIG. 3 is a top view of the partition.

We claim:

The ornamental design for a portable foldable partition, as shown.
